UNITED STATES PATENT OFFICE.

JAMES E. EATON, OF COLLINSVILLE, CONNECTICUT.

EDGE-TOOL.

SPECIFICATION forming part of Letters Patent No. 769,858, dated September 13, 1904.

Application filed September 17, 1903. Serial No. 173,504. (No model.)

To all whom it may concern:

Be it known that I, JAMES E. EATON, a citizen of the United States, residing in Collinsville, in the county of Hartford and State of Connecticut, have invented certain new and useful Improvements in Edge-Tools, of which the following is a specification.

This invention relates to the manufacture of edge-tools, and especially to that class of edge-tools which includes axes, hatchets, and analogous cutting implements.

In the manufacture of axes heretofore it has generally been customary to make the poll of iron or steel of a certain quality and to make the bit of a steel of such a quality that it will receive and retain a cutting edge. The bit has been attached to the poll in some instances by making a cleft in the poll and inserting a tongue or web of the bit and then welding down the flaps of the poll over the bit portion, such flaps overlying to a large extent the body of the bit and extending toward its cutting edge. Another method of the application of the bit-steel has been to make a shell or "overcoat" to overlie the extended end of the poll-piece, which would thereby make a part of the bit, so that in reality the bit of the ax would be organized of a piece of iron plated with a shell of steel. In both of these forms of construction objection is found, and it is the purpose of the present improvement to provide an ax wherein the cutting edge will be carried by a bit having a comparatively wide amount of clear metal and wherein the weld or seam between such bit portion and the poll portion will occupy considerable surface area, but will be restricted to a comparatively small longitudinal region and one wherein the lapping of the metal of the bit over the metal of the poll will give a considerable extent of surface for such welding, although in a restricted zone.

In the drawings accompanying and forming a part of this specification a form of my invention is illustrated, wherein—

Figure 1 is a side view of an ax-head. Fig. 2 is a perspective thereof, looking at the same from a back corner. Fig. 3 represents a central cross-section. Fig. 4 is a perspective of a form of stock for the bit, and Fig. 5 is a de-

tail in cross-section showing the initial application of the bit-stock to the poll portion.

Axes as generally constituted will comprise a poll (designated in a general way by 10) having therethrough an eye 11 for a handle and a bit (designated in a general way by 12) which will have a cutting edge 13. In carrying out my invention a suitable stock-blank, a form of which is illustrated in Fig. 4, may be provided and which is shown as comprising a stock portion 14 to make the major portion and cutting edge of the bit. From the stock portion are shown projecting at the sides and running longitudinally thereof a pair of flaps 15. The stock portion also carries a web 16, running longitudinally thereof and centrally disposed relative to the flaps. The portions 16 will be when the completed ax is presented an "insert" in the poll portion, and the wings or flaps 15 will act as an overcoat overlying the poll. The poll is seen as having a central cleft 17. Upon each side of the cleft are seen ribs or wings 18 to receive between them in the cleft the rib or wing 16 of the bit, and on each side of such wings 18 the wings or flaps 15 will be bent down and welded in any suitable manner. In the finished tool the inserted web 16 will extend toward the eye from the edge, and the outside or overlying flaps 15 will also project toward such eye and from the edge. It will be seen that the space or length between the upper points of the bit-flaps and the downward points of the poll-flaps is short compared with the entire length from the cutting edge to the eye and that the distance from the points of the poll-flaps to such cutting edge is also greater compared with the same length. By reference to Fig. 3 the upper line of the bit-flaps is represented by 20 and the lower line of the poll-flaps by 21. The line of the cutting edge is represented by 22, here shown as a point from which the lines 20 and 21 are struck, the line of the edge of course being transverse to the section-line of this figure. The lines of juncture will in practice vary, as is well known in the art of metal-working.

The terms "up" and "down" have been used herein for greater ease in description, such terms being suggested by the position the drawing occupies on the sheet.

In the ordinary overcoat method of applying a steel bit to an iron body-piece in the manufacture of this class of edge-tools the sides of the poll or body-piece form a relatively obtuse angle, and it will be evident, considering the nature of the materials employed, especially when in condition for welding, that a blow applied, for instance, about midway of the edges of the weld will by reason of the obtuseness of said angle tend to cause the material in the projecting portion of the body-piece to flow outwardly—that is, away from the bit—this result being due to the high degree of mobility of the metal, especially the middle of the body-piece, which is in such cases usually the softer portion, the result of this action being to cause the metal at the extreme end of the body-piece to draw away from the bottom of the bit-space rather than to entirely fill the same uniformly and evenly in all cases. As a result of such defective action the space which is usually present between the end of the body-piece and the bottom of the cleft in the bit when the parts are assembled for welding is sometimes not entirely filled, so causing a weakness of the edge of the tool and also causing a space which is liable to be opened up in the grinding of the tool when it is worn away far back from the original edge. In this connection it will be remembered that in this class of edge-tools it is an ordinary practice to repeatedly forge and retemper the edge of the tool, especially in cases of axes and heavy knives. For overcoming the objections to which I have referred I provide the overcoat form of bit (indicated in a general way by 14) with a supplemental flange portion 16, located about midway of the two overcoat-flanges 15 of the bit-blank. When such a bit-piece is applied to the body-piece 10—as, for instance, in Fig. 5, wherein it has a cleft 17, forming its edge into two flaps 23 23, the said supplemental or central flange 16 being relatively thin and the sides 24 24 of the body-piece or portion considered in relation to the central flange forming comparatively acute angles—an immediate result is to reduce the angle of the space between said center flange and of the respective walls 24 24 to a relatively small angle materially more acute than the angle of the walls of the body-piece in a tool made according to the original overcoat form of construction. The result of this is to reduce by a substantial amount in such a case as indicated the tendency of the body portion to be driven out of the bit by the blow of the welding hammer or die. In this connection it will be noted that the result of the welding operation is modified by the adhesion of a portion of the engaging surfaces when the welding action first begins, so that with my improved construction the initial adhesion of the surfaces takes place at the beginning of the die action, whereby as the

parts are welded together the welding action operates upon a thinner mass of metal—that is, upon a thinner projection of the body-piece—so that the distance through which the flowage and the force applied to the body-piece is much less, and the consequent intensity and the certainty of the forging action is correspondingly increased. The result of these features of my present invention is to materially assist in so joining together the two parts of the tool as to cause the edges of the projecting flanges of the body-piece to normally flow partly outwardly and partly inwardly of the bit-blank spaces, thus tending to entirely fill the spaces 25 25 and 17 at the bottom of the clefts in the respective portions being welded and so operating to facilitate the making of a perfect weld throughout the entire length of the juncture between said portions of the tool. 85

By this form of construction the space consumed by the flap is small or short, but the area wherein the metal meets the other in the weld is comparatively large. There is by this means given a large amount of clear edge-receiving metal, and the edge or flaps of such metal where they join the poll overlying the same and projecting toward the eye give a large surface of the hard metal upon the outside of such sides from the edge upward as large as 95 or larger than the face given by what is known as the "overcoat" construction of ax, but with a larger amount of such metal to wear down in repeated sharpenings, and it will also be seen that the central portion of the 100 bit enters the poll and is as far as or farther from the cutting edge than the similar portions of what is known as the "inserted" bit, whereby not only does this present the advantages of both of such forms of construction, 105 but it presents its own peculiar advantages without any of the disadvantages of such other constructions and produces an ax the edge-carrying portion of which is of a greater length and will permit of more frequent sharpenings than those made by the various methods heretofore employed. 110

Although the drawings herein illustrate the practical application of this invention in connection with an ax, yet it will be apparent 115 that it is capable of incorporation into many forms of edge-tools, and I do not limit myself to any one tool.

Having thus described my invention, I claim— 120

1. A tool having bit and poll of metal of different characteristics, the bit having a tongue or web and flaps the tongue extending into the poll for some distance and the flaps overlying the poll and extending on the outside thereof substantially as far as does the tongue on the inside. 125

2. In an ax or similar tool, the combination with a poll having an eye, of an edge-carrying bit having flaps overlapping the poll toward 130

the eye and welded thereto, a web from the bit entering the poll and welded thereto, its area of weld being equal to the area of weld of the flaps, the poll being provided with a 5 pair of flaps located between the respective flaps on the bit and the web, whereby a comparatively large area is embraced in the welded juncture in a comparatively short zone.

3. An ax or similar tool comprising a bit 10 having two comparative long lips lapped and welded over the poll, and a web entering the poll and welded thereto, the area of the weld of the web being substantially equal to that of the welded area of the lips.

15 4. The combination with an ax or similar tool having a poll provided with an eye, of an edge-carrying bit having flaps overlapping the sides of the poll and welded thereto, the direction of the lap being toward the eye of the 20 poll and away from the edge of the bit, a web from the bit entering the poll for some distance, welded thereto, extending in the general direction of the outside lips and having a welded area substantially equal to that of the 25 lips, and a comparatively long edge-receiving portion clear of the metal of the poll.

5. The combination with an ax or similar tool having a poll provided with an eye, of an edge-carrying bit having portions overlapping 30 the sides of the poll and welded thereto, the direction of the lap being toward the eye and away from the edge, and a web from the bit entering the poll and extending in the general 35 direction of the laps and having a welded area substantially equal to that of the laps.

6. An ax or similar tool comprising a bit and a poll welded thereto, the poll having two comparatively long lips of substantially equal area, and the bit having three comparatively long lips of substantially equal area, one interposed between the lips of the poll and the others overlapping the same. 40

7. As an article of manufacture, a blank for an ax or similar tool bit comprising a stock portion, a longitudinal flap carried by each 45 side thereof and having a face adapted to be welded to a poll, and a longitudinal web carried by the stock and disposed centrally thereof and of the flaps and having faces adapted to be welded to said poll and substantially equal 50 in welding area to the welding area of said flaps.

8. An edged tool comprising a welded bit and poll each of a different grade of metal, the bit having a substantial web projecting into a cleft 55 or recess in the poll and overlapped by a pair of substantial webs of such poll and having a pair of flaps of substantial length exteriorly overlapping the webs of such poll, the structure being such that the tool may be sharpened 60 to a greater extent without eliminating the lap-joint than if a web of the poll projected centrally into the bit, and having prior to such extended sharpening a superior exterior surface for a greater part of its area than if the 65 poll exteriorly overlapped the bit.
